UNITED STATES PATENT OFFICE.

JOHN S. WERTZ, OF STANBERRY, MISSOURI.

CAR-SEAL.

SPECIFICATION forming part of Letters Patent No. 286,514, dated October 9, 1883.

Application filed December 19, 1882. (No model.)

To all whom it may concern:

Be it known that I, J. S. WERTZ, a citizen of the United States, residing at Stanberry, in the county of Gentry and State of Missouri, have invented certain new and useful Improvements in Car-Seals; and I do hereby declare the following to be a full, clear, and exact description of the invention, such as will enable others skilled in the art to which it appertains to make and use the same.

My invention relates to that class of seals which are made use of for sealing baggage and railway cars; and the nature thereof consists in certain improvements in the construction of the same, hereinafter described.

In the accompanying drawings, Figure 1 represents the seal as it appears in use. Fig. 2 is a longitudinal section representing the ends connected and locked together. Fig. 3 represents the ends detached. Fig. 4 represents the blank or piece of metal brought to the required shape for the finishing operation.

A piece of tin is cut to form a blank of the required form, as is shown in Fig. 4. This blank is provided with projections *b* and *c*, the latter of which is doubled back upon the blank,

as is clearly indicated in Fig. 2, which represents in longitudinal section the ends connected and locked together in such a manner as to form a receptacle for the end *d*, which is also doubled back upon the blank, as shown best in Fig. 3. This bent end *d* is made to interlock with the bent end *c*, as is clearly shown in Fig. 2, and the part *b* is bent over the interlocked parts, as is best shown in Fig. 1. The material used in constructing the seal is frangible tin or some other frangible metal, which will be fractured should an attempt be made to tamper with the device or disengage its parts.

I claim and desire to secure by Letters Patent of the United States—

A car-seal blank consisting of the strip *a*, having the lateral extension *b* and end extensions, *c* and *d*, as and for the purposes described.

In testimony whereof I affix my signature in presence of two witnesses.

JOHN S. WERTZ.

Witnesses:

L. W. AXTON,
W. CHAMBERLIN.
